ENGINE STARTER GEARING

James J. Digby, Elmira, N. Y., assignor to Bendix Aviation Company, Elmira Heights, N. Y., a corporation of Delaware

Application November 27, 1946, Serial No. 712,704

7 Claims. (Cl. 74—7)

1

The present invention relates to engine starter gearing and more particularly to an improved form of "anti-kickout" type of starter drive.

It is an object of the present invention to provide a novel starter drive of the automatically engaging type incorporating manually controlled means for maintaining the engagement of the drive with the engine member.

It is another object to provide such a device in which the drive unit is completely self-contained so as to require no external stop or abutment on the drive shaft to arrest the travel of the drive pinion.

It is another object to provide such a device which is adapted to be used without alteration either as an inboard or outboard type of drive.

It is another object to provide such a device which incorporates means for limiting the torque capacity of the drive so as to prevent overloading the transmission.

It is another object to provide such a device incorporating a connection which permits the drive pinion to overrun freely when the engine fires, while insuring prompt and positive reengagement of the drive if the engine should not continue to be self-operative.

It is another object of the invention to provide such a device incorporating means for insuring a rapid and quiet disengagement of the drive pinion when the operator deenergizes the starting circuit and releases the pinion from its engaged position.

It is another object to provide such a device in which the pinion and the parts associated with it are so formed and mounted as to have extended bearing surfaces for maintaining proper alignment of the parts, and enabling them to overrun the power shaft at high speeds over extended periods of time without excessive wear or danger of seizure of the bearings.

It is another object of the invention to provide such a device incorporating an elastically compressible member forming a yielding driving connection, with means for maintaining said member under compression at all times while limiting the maximum compression thereof.

Further objects and advantages will be apparent from the following description taken in connection with the accompanying drawing, in which:

Fig. 1 is a side elevation partly in section of a preferred embodiment of the invention showing the parts in normal or idle position;

Fig. 2 is a similar view showing the parts in cranking position; and

2

Fig. 3 is a similar view showing the parts in the positions assumed when the engine fires and causes the pinion to overrun the drive shaft.

In Fig. 1 of the drawing, there is illustrated a power shaft 1 which is preferably the extended armature shaft of a starting motor, a fragment of which is illustrated at 2. A screw shaft 3 is fixed on the power shaft 1 as by means of a cross pin 4 which is retained in position by a flanged ring 5 seated against a shoulder on the screw shaft.

A pinion 7 is slidably journaled on the power shaft for movement into and out of mesh with a gear 8 of the engine to be started, and means 15 for actuating the pinion from the screw shaft 3 is provided comprising a control nut 9 threaded on the screw shaft and a connection between the control nut and pinion comprising a yielding clutch means and an overrunning clutch. For this purpose, a flange member 11 is non-rotatably mounted on the control nut against a shoulder 12 thereon, and the control nut is provided with a counterbored extension 13 on which is slidably journaled a driving overrunning clutch member 14, retained thereon by a split lock ring 15. A cylindrical block 16 of elastically deformable material such as rubber is seated on the control nut between the flange 11 and the clutch member 14, being retained under suitable initial compression therebetween by the lock ring 15. A wear ring 17 may be interposed between the end of the rubber block 16 and the clutch member 14 if deemed desirable. A second lock ring 18 is located on the extension 13 of the control nut 9 in position to engage the clutch member 14 after a predetermined compression of the rubber block 16 so as to limit the compression of said block and thereby limit the torque capacity of the friction clutch connection between said block and the clutch member.

The pinion 7 is provided with a cylindrical extension or hub 19 on which a driven overrunning clutch member 21 is fixedly mounted in any suitable manner. The adjacent faces of the driving and driven overrunning clutch members 14, 21 are provided with inclined teeth 22, 23 respectively as best shown in Fig. 3, the inclination of the teeth being such as to facilitate overrunning of the pinion when the engine starts. The extension 19 of the pinion 7 is preferably provided with a bushing 24 forming a pilot bearing for the interior of the extension 13 of control nut 9, whereby the control nut, clutch members and pinion are maintained in proper alignment so as to prevent seizure or binding of the parts.

Means for defining the meshing position of the pinion 7 is provided comprising a barrel member 25 which encloses the screw shaft 3 and the driving connection to the pinion. Barrel 25 has an abutment 26 at one end adapted to engage the end of the screw shaft, and a stop in the form of an inturned flange 27 at its other end in the path of movement of a radial flange 28 on the driven clutch member 21. A spiral spring ring 29 of rectangular cross-section is interposed between the flange 28 of the driven clutch member and stop 27 of the barrel, and serves to yieldingly press the clutch members 14, 21 into engagement. Ring 29 also serves as a washer when it is compressed flat during the driving operation as shown in Fig. 2.

The barrel 25 is provided with an internal shoulder 31 forming an abutment for the flange 21 of the control nut 9. A latch ring 32 is rotatably mounted on the barrel adjacent said shoulder, being retained in position by a split lock ring 33. Manually controlled means cooperating with the latch ring 32 are provided for holding the pinion 7 in mesh with the engine gear 8. This means comprises a plunger 34 which is movable by the operator into engagement with the latch ring 32 as shown in Fig. 2 whereby backward movement of the barrel is limited as shown in Fig. 3. It will be understood that this plunger may be an extension of the starting switch plunger or actuated concurrently therewith in the manner set forth in the application to Oliver, Ser. No. 653,775, assigned to the assignee of the present application.

Yielding means for normally holding the parts in idle position is provided in the form of a compression spring 35 seated at one end on the flange ring 5, and bearing at its other end against the abutment 26 of the barrel.

In operation, starting with the parts in the positions illustrated in Fig. 1, energization of the starting motor causes rotation of the power shaft 1 in the direction of the arrow "a" whereby the control nut 9 shifts the longitudinally movable parts of the drive to the right until the abutment 26 of the barrel engages the end of the screw shaft 3. The stop flange 27 of the barrel thereupon arrests the longitudinal movement of the pinion, and further movement of the control nut compresses the rubber block 16 against the driving clutch member 14, forcing the latter against the driven clutch member 21 until such time as sufficient torque is built up to cause the pinion to rotate the engine gear 8. If the initial load caused by the engagement of the pinion with the stationary engine gear exceeds a predetermined maximum, further compression of the rubber block 16 is prevented by engagement of the lock ring 18 with the driving clutch member 14, after which an increase in torque may cause slippage to take place between the rubber block and driving clutch member thus slipping off the excessive load and thereby protecting the parts of the drive.

Concurrently with energization of the starting motor, the plunger 34 is caused by the operator to be pressed against the exterior of the barrel 25, whereby the plunger enters a recess 36 in the latch ring 32 when it comes into registry therewith.

When the engine fires, the acceleration of the pinion 7 thereby is transmitted to the control nut to cause it to overrun the screw shaft 3 sufficiently to permit the clutch member 14 to overrun the clutch member 21. Further retrograde move-

ment of the control nut is prevented, however, by the engagement of the latch ring 32 with plunger 34 as shown in Fig. 3. The pinion 7 is thereafter free to overrun the drive while driven clutch member 21 is held against the driving clutch member 14 by the clutch spring 29. If the engine fails to continue self-operative, as soon as the pinion slows down to the speed of the power shaft, the clutch members 14, 21 reengage, and cranking is resumed. When the operator is satisfied that the engine is reliably self-operative, he deenergizes the starting motor and at the same time withdraws the plunger 34 from its engagement with the latch ring 32. The anti-drift spring 35 thereupon becomes effective to press the clutch members 14, 21 together thereby increasing their frictional drag, and at the same time urges the parts toward idle position, whereby the acceleration of the pinion by the engine gear together with the pressure of the anti-drift spring serves to quickly and quietly draw the pinion out of mesh with the engine gear.

Although but one form of the invention has been described in detail, it will be understood that other embodiments are possible and that changes may be made in the design and arrangement of the parts without departing from the spirit of the invention as defined in the claims appended hereto.

What is claimed is:

1. In an engine starter drive, a power shaft, a screw shaft fixed thereon, a pinion having an extended hub slidably journaled on the power shaft for longitudinal movement into and out of mesh with a gear of an engine to be started, a control nut threaded on the screw shaft having an extension slidably journaled on the hub of the pinion, a yielding driving member of elastically deformable material seated on the control nut, a driving clutch member journaled on the control nut having a frictional driving connection with the yielding driving member, a driven clutch member fixed to the pinion, yielding means for urging the clutch members into engagement, and means for positively limiting the meshing movement of the pinion.

2. An engine starter drive as set forth in claim 1, including further, means on the control nut holding the driving clutch member and yielding driving member under initial compression.

3. An engine starter drive as set forth in claim 1, including further, means on the control nut for limiting the compression of the yielding driving member.

4. An engine starter drive as set forth in claim 1 in which said driving clutch member is slidably journaled on the extension of the control nut, and including further, stop means on said extension of the control nut to limit the longitudinal movement of the driving clutch member thereon.

5. An engine starter drive as set forth in claim 1 in which the means for limiting the meshing movement of the pinion comprises a barrel enclosing the drive having an abutment at one end adapted to engage the screw shaft and a stop for the driven clutch member at the other end.

6. An engine starter drive as set forth in claim 1 in which the means for limiting the meshing movement of the pinion comprises a barrel enclosing the drive having an abutment at one end adapted to engage the screw shaft and a stop for the driven clutch member at the other end; and including further, yielding means urging the barrel in the direction to demesh the pinion, and manually controlled means for ar-

resting the demeshing movement of the barrel, so as to maintain the pinion in mesh with the engine gear.

7. An engine starter drive as set forth in claim 1 in which the means for limiting the meshing movement of the pinion comprises a barrel enclosing the drive having an abutment at one end adapted to engage the screw shaft and a stop for the driven

clutch member at the other end, the yielding means for engaging the clutch members comprising a spring located between the driven clutch member and the stop on the barrel, said screw shaft having a flange, and a demeshing spring compressed between the abutment on the barrel and the flange on the screw shaft.
